UNITED STATES PATENT OFFICE

112,001

DESIGN FOR A BELT OR SIMILAR ARTICLE

Shepard Solomon, New York, N. Y.

Application August 20, 1938, Serial No. 79,472

Term of patent 3½ years

To all whom it may concern:

Be it known that I, Shepard Solomon, a citizen of the United States and a resident of the city of New York, Borough of the Bronx, county of Bronx, and State of New York, have invented a new, original, and ornamental Design for a Belt or Similar Article, of which the following is a specification, reference being had to the accompanying drawing forming part thereof, in which—

Figure 1 is a perspective view of a belt or similar article embodying my new design;

I claim:

The ornamental design for a belt or similar article, substantially as shown.

SHEPARD SOLOMON.
